UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

STITCH-FORMING MECHANISM FOR SEWING-MACHINES.

1,334,626.

Specification of Letters Patent. Patented Mar. 23, 1920.

Application filed June 16, 1915. Serial No. 34,425.

To all whom it may concern:

Be it known that I, JAMES R. MOFFATT, a citizen of the United States, residing at Chicago, in the county of Cook, State of Illinois, have invented certain new and useful improvements in Stitch-Forming Mechanism for Sewing-Machines, of which the following is a description, reference being had to the accompanying drawing and to the figures of reference marked thereon.

The invention relates to new and useful improvements in stitch forming mechanism for sewing machines, and more particularly to the cross thread laying mechanism which coöperates with the needles above the work support.

An object of the invention is to provide a cross thread laying mechanism, wherein the thread laying implement is actuated by a positively operated train of mechanism including as one of its elements the auxiliary presser bar.

A further object of the invention is to provide a machine of the above character having two thread laying implements with devices whereby said implements may be operated simultaneously in opposite directions from the same actuating arm carried by the auxiliary presser bar.

These and other objects will in part be obvious and will in part be hereinafter more fully disclosed.

In the drawings, which show by way of illustration one embodiment of the invention,

Figure 1 is a rear view of a sewing machine embodying my improvements;

Fig. 2 is an end elevation of the same, certain of the parts being omitted to avoid confusion;

Fig. 3 is a view partly in section and partly in top plan, showing a portion of the work support, presser foot, the needle bar, the thread laying devices and the means for operating the same from the auxiliary presser bar;

Fig. 4 is a similar view showing the thread laying fingers in different positions;

Fig. 5 is a detail, partly in section and partly in rear elevation, showing the manner of supporting the thread laying fingers on the presser bar;

Fig. 6 is a detail, showing one of the con-

nections between the main presser bar and the auxiliary presser bar;

Fig. 7 is a sectional view on the line 7—7 of Fig. 6;

Fig. 8 is a sectional view on the line 8—8 of Fig. 4;

Fig. 9 is a detail in plan, showing the operating rocker for one of the thread laying fingers;

Fig. 10 is a similar view, showing the rocker for the other thread laying finger;

Fig. 11 is a view more or less diagrammatic, showing the train of mechanism between the thread laying fingers and the horizontal operating shaft at the rear of the machine;

Fig. 12 is a view showing diagrammatically the position of the needles and the thread laying fingers on one stroke of the needles;

Fig. 13 is a similar view, showing the position of the thread laying fingers on the next stroke of the needles; and

Fig. 14 is a diagrammatic view, showing the position of the cross threads relative to the needle threads in the finished seam.

I have shown my improved thread laying mechanism as applied to a sewing machine having a bed 1, which carries a work support 2. A standard 3 is also supported on the bed and carries an overhanging arm 4. A needle bar 5 reciprocates in the supporting head 6 at the forward end of the overhanging arm 4. This needle bar is reciprocated by a needle lever 7, which is oscillated by an eccentric strap 8 coöperating with an eccentric on the main shaft 9. The needle bar 5, as herein shown, is provided with three needles 10, 11 and 12. Coöperating with the needles beneath the work support is a single looper 13, see Figs. 12 and 13. This three needle stitching mechanism is well known in the art and further description thereof is not thought necessary.

The material to be stitched is fed to the needles by a feed dog 14, which is operated in the usual way. Coöperating with the feed dog 14 is a presser foot 15, which is carried by a presser bar 16. This presser bar is mounted so as to slide freely in the supporting head 6 and may be raised by a hand lever 17 or a lever 18 which may be connected to a suitable treadle. A spring 19

operates to hold the presser bar on the work support.

Coöperating with the needles, as herein shown, are two thread carrying fingers 20 and 21. The thread carrying finger 20 is clamped to an arm 22 which projects laterally from a rocking frame 23. Said finger is held on the arm by a suitable set-screw 24. The thread laying finger 21 is carried by an arm 25 which projects laterally from a rocking frame 26 and said finger is secured to the arm by a similar set-screw. These rocking frames 23 and 26 are mounted one above the other on the presser bar 16. Said presser bar is provided with a bearing collar 27 located directly above the presser foot and the rocking frame 26 rests thereon. A collar 28 carried by the presser bar 16 and secured thereto by a set screw, engages the upper face of the rocking frame 23 for the thread finger 20. The rocking frame 23 has a second arm 29, which carries a pin 30. A link 31 engages this pin 30 at one end and at its other end said link freely engages a pin 32 carried by an arm 33 fixed to the auxiliary presser bar 34. The rocking frame 26 is provided with a second projecting arm 35, which carries a pin 36. A link 37 engages at one end this pin 36 and at its other end said link engages the pin 32 carried by the arm 33. Said pin 32 is clamped to the arm 33 by a set screw 38 and said pin has a head 39 in its lower end, so that the links 31 and 37 freely engage the pin and are held thereon. The auxiliary presser bar 34 is mounted so as to reciprocate and also oscillate in the supporting head 6 of the machine. Said main presser bar 16 has two laterally projecting upper and lower guiding arms 40 and 41 which are fixed to the presser bar and these arms at their rear ends are forked, as at 42, the fork of the arm 41 straddling a block 43 which is freely mounted on the auxiliary presser bar and said block is provided with a flanged head 44 to prevent the same from falling through the fork. The fork of the arm 40 also straddles a similar block. A collar 45 is rigidly attached to the auxiliary presser bar directly above the block 43. These arms 40 and 41 prevent the main presser bar 16 from oscillating in its supporting bearings and the fixed collar 45 insures that the auxiliary presser guide bar is lifted with the main presser bar 16. The block 43 has a free connection with the auxiliary presser bar and permits the latter to oscillate. Said auxiliary presser bar is provided with a laterally projecting arm having a ball stud 46. A link 47 engages this ball stud at one end and at its other end engages a ball stud 48 carried by a crank pin fixed to the shaft 49. The shaft 49 is a horizontal shaft and is mounted in the bearings 50 and 51 at the rear of the machine. Said shaft 49 carries

a rearwardly projecting arm 52 which also has a ball stud for the eccentric strap 53.

The eccentric strap 53 coöperates with an eccentric on a stub-shaft mounted in a bearing 54 carried by the standard 3 and this stub-shaft carries a gear wheel 55 which meshes with a gear wheel 56 on the main shaft 9. The gear wheel 55 is double the size of the gear wheel 56, so that the stub-shaft is rotated once for every two rotations of the main shaft. This rotation of the stub-shaft through the eccentric strap 53 oscillates the shaft 49 giving one complete oscillation thereto for each rotation of the stub-shaft. As the shaft 49 oscillates the link 47 will oscillate the auxiliary presser bar 34 and this in turn will oscillate the arm 33 at the lower end thereof. The oscillations of the arm 33 will be imparted through the links 31 and 37 to the rocking frames 23 and 26, respectively. Inasmuch as the connections to these rocking frames are on opposite sides of the longitudinal axis of the presser bar, said thread fingers carried by the rocking frames will be moved respectively in opposite directions.

I have shown diagrammatically in Fig. 12 the needles raised and the looper in its forward position. The thread fingers 20 and 21 are retracted and the threads *a* and *b* of these thread fingers respectively extend from the thread fingers to the opposite sides of the seam where they were previously interlocked with the needle threads. The needles on their downward movement pass in front of these threads *a*—*b*. The thread fingers 20 and 21 move forward to the position shown in Fig. 13, so that, when the needles are again at the upper end of their stroke, the threads *a* and *b* of the thread fingers are crossed in the opposite direction in rear of the needles, so that on the next descent of the needles they will pass again in front of the needles.

It will thus be seen that the threads are laid in front of the needles on a movement of the thread fingers in one direction for each complete stroke of the needles, so that in the resulting seam the threads are crossed between each set of needle punctures, as clearly shown in Fig. 14, wherein the needle threads are indicated at *c*, *d* and *e*, respectively, for the needles 10, 11 and 12.

From the above description, it will be apparent that I have provided a positive train of mechanism for actuating the thread fingers which includes as one of its elements the auxiliary presser bar, and this greatly simplifies the construction of the mechanism for actuating the thread fingers, and that the fingers are supported by and movable with the presser bar, this allowing the foot to be raised without interfering with said fingers. Furthermore, the connecting parts are relatively short in length and free from lateral

vibration during the actuation of the machine, and, therefore, the machine is particularly adapted for high speed stitching.

While I have shown two thread fingers, it will be obvious that my improved cross thread laying mechanism may be applied to a stitching mechanism wherein one cross thread is laid back and forth for engagement with the needle threads. It is also obvious that minor changes in the details of construction and arrangement of parts may be made without departing from the spirit of the invention, as set forth in the appended claims.

Having thus described my invention, what I claim as new and desire to secure by Letters Patent, is:

1. The combination with a work support, a presser foot, a main presser bar carrying said presser foot, needles, means for reciprocating said needles, of cross thread laying mechanism located above the work support including a thread carrying finger for continuously guiding the cross thread, a supporting arm for said finger, said arm being mounted to oscillate about the axis of the presser bar and movable up and down with said presser bar, a vertical shaft located exterior of the presser bar and movable up and down with said presser bar, means for oscillating said vertical shaft, and means for connecting said vertical shaft to said supporting arm for oscillating said thread laying finger.

2. The combination with a work support, a presser foot, a main presser bar carrying said presser foot, needles, means for reciprocating said needles, of cross thread laying mechanism located above the work support including a thread laying finger for continuously guiding the cross thread, an arm supporting said thread laying finger, said arm being mounted to oscillate about the axis of the presser bar and movable up and down with said presser bar, an auxiliary presser bar movable up and down with said main presser bar, means for oscillating said auxiliary presser bar, and means for connecting said auxiliary presser bar with said arm for oscillating the latter.

3. The combination with a work support, a presser foot, a main presser bar carrying said presser foot, needles, means for reciprocating said needles, of cross thread laying mechanism located above the work support including a thread laying finger for continuously guiding the cross thread, a rocking frame carrying said finger, said frame being mounted to oscillate about the axis of the presser bar and movable up and down therewith, an auxiliary presser bar movable up and down with said main presser bar, a horizontal shaft, means for oscillating said shaft, means for connecting said horizontal shaft to said auxiliary presser bar for oscil-

lating the latter, and means for connecting the lower end of said auxiliary presser bar with said rocking frame for oscillating the thread laying finger.

4. The combination with a work support, 70 a presser foot, a main presser bar carrying said presser foot, needles, means for reciprocating said needles, of cross thread laying mechanism located above the work support including thread laying fingers, a separate 75 supporting shank for each finger, said shanks being mounted to oscillate freely on the presser bar and move up and down therewith, an auxiliary presser bar moving up and down with said main presser bar, an 80 arm extending laterally from said auxiliary presser bar, links connecting said arm respectively with the supporting shanks for the thread fingers on opposite sides of the presser bar, and means for oscillating said 85 auxiliary presser bar.

5. The combination with a work support, a presser foot, a main presser bar carrying said presser foot, needles, means for reciprocating said needles, of cross thread laying 90 mechanism located above the work support including thread laying fingers, a separate supporting shank for each finger, said shanks being mounted to oscillate freely on the presser bar and move up and down therewith, an auxiliary presser bar moving up and down with said main presser bar, an arm extending laterally from said auxiliary presser bar, links connecting said arm respectively with the supporting shanks for 95 the thread fingers on opposite sides of the presser bar, a horizontal shaft, an arm projecting downwardly from said shaft, a second arm carried by the auxiliary presser bar, and a link for connecting the arm of the 100 horizontal shaft with the arm of the auxiliary presser bar.

6. The combination with a work support, a presser foot, a main presser bar carrying said presser foot, needles, means for reciprocating said needles, of cross thread laying mechanism located above the work support including thread fingers located on opposite sides of the needles, an annular supporting shank for each thread finger, said shanks 110 being mounted to oscillate on the presser foot, a bearing washer on which said shanks rest, a collar secured to the presser bar above said shanks, each shank having an arm projecting outwardly therefrom, said 115 arms being located on opposite sides of the center of the presser bar, an auxiliary presser bar connected to said main presser bar and movable up and down therewith, an arm projecting laterally from said auxiliary 120 presser bar, a headed pin carried by said arm, links freely engaging said pin and pivoted respectively to the arms carried by said shanks, and means for oscillating said auxiliary presser bar.

7. The combination with a work support, a presser foot, a main presser bar carrying said presser foot, needles, means for reciprocating said needles, of cross thread laying mechanism located above the work support including a thread laying finger for continuously guiding the cross thread, an arm supporting said thread laying finger, said arm being mounted to oscillate about the axis of the presser bar and movable up and down with said presser bar, an auxiliary presser bar, means for oscillating said auxiliary presser bar, and means for connecting said auxiliary presser bar with said arm for oscillating the latter.
8. The combination of a work support, a needle bar, a plurality of needles carried thereby, a presser bar, a presser foot, an auxiliary presser bar and cross thread laying mechanism including thread guiding fingers mounted on the presser bar and movable up and down therewith, said fingers being respectively disposed on opposite sides of the needles, means for oscillating said

auxiliary presser bar and means for operating said thread guiding fingers from said auxiliary presser bar.

9. The combination of a work support, a needle bar, a plurality of needles carried thereby, a presser bar, a presser foot, an auxiliary presser bar and cross thread laying mechanism including thread guiding fingers mounted on the presser bar and movable up and down therewith, said fingers being respectively disposed on opposite sides of the needles, means for oscillating said auxiliary presser bar and means for operating said thread guiding fingers from said auxiliary presser bar, said thread guiding fingers being so disposed as to cross the line of seam in different horizontal planes.

In testimony whereof, I affix my signature in the presence of two witnesses.

JAMES R. MOFFATT.
